UNITED STATES PATENT OFFICE.

JESSE ALEXANDER, OF NEW YORK, N. Y., ASSIGNOR OF ONE-HALF TO HERBERT W. LITTLE, OF NEW YORK, N. Y.

TYPE-WRITING-MACHINE RIBBON FEEDING AND OPERATING MECHANISM.

1,077,238.

Specification of Letters Patent.

Patented Oct. 28, 1913.

Application filed November 4, 1912. Serial No. 729,927.

To all whom it may concern:

Be it known that I, JESSE ALEXANDER, a citizen of the United States of America, and residing at New York, in the county of 5 Kings and State of New York, have invented new and useful Improvements in Type-Writing-Machine Ribbon Feeding and Operating Mechanism, of which the following is a specification.

10 My invention relates particularly to mechanism adapted for use in a front stroke or visible writing machine.

15 The main object is to provide a simple and readily operable mechanism for feeding the ribbon step by step across and in front of the platen, raising and lowering the ribbon at the printing point and reversing the direction of feed of the ribbon when desired and varying the lift of the ribbon so 20 as to correspond with the changes of height of the printing type.

In the form of mechanism shown the operation is effected by the type bar operating the universal bar. Two ribbon spools are 25 removably mounted on opposite sides of the machine and retained in position by a spring pressed frame which also affords frictional retardation. These ribbon spools are mounted on the shafts of horizontal ratchets 30 which are adapted to be rotated step by step by spring pressed pawls. Spring retaining pawls are also provided for preventing backward rotation during the feeding stroke. The ribbon is guided at the printing point by a vertical moving guide. The height of this vertical movement is variable 35 with the shifting of the platen. Both of the feeding pawls and the ribbon lifting device are connected to the universal bar and operate intermittently therewith. The support for the lifting device is carried by a part of the platen shifting mechanism so as to vary the lift of the ribbon guide. The 40 direction of feed of the ribbon may be reversed by a laterally shifting bar having cam surfaces for retracting one or the other of the feeding pawls and the corresponding retaining pawl.

Figure 1, is a vertical sectional view of a 45 machine embodying my invention showing the parts in their normal position of rest this view being taken on a plane principally at the right of the right-hand shift key lever in Fig. 3. Fig. 2, is a fragmentary sectional view showing the parts in the print-

ing position certain of the parts being omitted to render the operation clearer. Fig. 3, is a plan view. Fig. 4, is a rear view and partial section. Fig. 5, is a vertical sectional view showing the method of supporting one of the ribbon spools. Fig. 6, is a detail view of one end of the ribbon reversing rod indicating how the feed pawl rests thereon and is directly operated thereby. Fig. 7, is a perspective view showing the 65 ribbon feeding pawls.

The ribbon 1, is wound from side to side on spools 2, 2. Each spool is mounted to rotate with the upper end of the shaft 3 which has bearings in the plate 4 and a 70 ratchet 5 on its lower end. A U-shaped frame has a pivot shaft 6 and two arms 7 and 8 embrace the lower and upper faces of the ribbon spool. The pivot shaft 6 of this frame is under tension of the spring 9 75 so as to press the arm 7 against the collar 10 fixed to the shaft 3 and thus frictionally retard the rotation of the shaft 3 and the ribbon spool 2. The collar 10, being fast upon the spool shaft 3, serves to support the 80 shaft in its bearing. The upper arm 8 of the spool holding frame overstands the upper face of the spool and holds the spool in position. The frame however, may be retracted by pressing on the extended portion or finger-piece of the lower arm 7 (see Fig. 3) so as to enable one to remove or replace the ribbon spool.

At the printing position the ribbon is guided by a frame or yoke or guide 11 which 90 is vertically movable. The type bar 12 is pivoted in the type bar segment 13 and adapted to operate the universal bar 14 which is suspended at 15 from the swinging member 16. A spring 17 is interposed between the abutment 18 and the adjustable screw 19 carried by the universal bar so as to press the universal bar toward the back 95 of the type bar segment. The lever 20 pivotally supported at 21 has its front end 100 hinged to the lower end of the ribbon guide 11 and its upper end hinged to the link 22 which is pivoted at 23 to the universal bar. When the universal bar is moved to the rear the pivot 23 carries the link 22 to the rear and tilts the lever 20 about its pivot 21 so as to lift the ribbon guide 11. When the type bar rebounds from the printing position, the universal bar is released and the spring 17 forces it forward carrying with 110

it the pivot 23 and link 22 and thus tilting the front end of the lever 29 downward and dropping the ribbon guide 11 from in front of the platen 24.

5 In order to vary the lifting stroke of the guide 11 I support the pivot 21 in the yoke 25 which depends from the bar 26 pivoted in the sides of the machine. This bar constitutes part of the platen shifting mechanism and has arms such as 27 connected to the platen shifting yoke 28. Opposite ends of the bar 26 have arms 29, 29 at opposite sides of the machine connected to the shifting key levers 30, 30, the connection being 15 by a link such as 32. When a shift key lever is depressed, it draws downward the link 32 and arm 29 and rocks the bar 26 and its depending yoke 25 forwardly thus carrying forward the pivot 21. This lifts 20 the ribbon guide since the upper end of the lever 20 is at this time connected by the link 22 to the pivot 23 which is relatively stationary. Now when a type bar lever is depressed the ribbon guide is elevated 25 through the action of the universal bar and link 22 in the manner previously described and this lifting movement being added to the movement which has already been given the ribbon guide through the medium of the 30 shift key and parts just described causes the guide to be lifted an additional distance sufficient to carry the ribbon up into position for printing in the upper case. The guide may be locked in its upper position 35 indirectly by locking one of the shifting key levers 30 as for instance, by means of a spring pressed latch 33 and a pin 34 projecting from the shift key lever.

The feeding is accomplished by pawls 40, 40 only one of which however, is adapted to operate at one time. Each pawl is hinged to an arm 41 which extends upwardly from the shaft 42 and the latter is connected by an arm 43 to the universal bar 41. When 45 the universal bar moves to the rear it rocks the shaft 42 and moves the feeding pawls forward. When the universal bar returns, the pawls 40, 40 move to the rear and one or the other of them feeds its ratchet. A 50 spring pressed retaining pawl 44 is mounted adjacent each of the feeding pawls 40 for preventing backward rotation. The retaining pawl presses lightly on the top of the feeding pawl to assist in holding it against 55 the ratchet.

In order to shift the direction of feed of the ribbon I provide a laterally shifting rod 45 which has cam surfaces at its ends such as 46 and 47 on which the feeding pawls 60 rest. When the bar is in position so that the feeding pawl rests on the surface 47, the pawl is permitted to engage its ratchet and feed the same. When the bar is shifted

laterally, the surface 46 comes beneath the feeding pawl and lifts it away from the ratchet. The cams on the opposite ends of the rod 45 are so designed that when one feeding pawl is disengaged from its ratchet the other feeding pawl engages its ratchet and vice-versa. The lifting of a feeding pawl also lifts indirectly the corresponding retaining pawl through the intervention of the feeding pawl.

What I claim is:—

1. Ribbon feeding mechanism comprising 75 vertical ribbon shafts, horizontal ratchets carried thereby, a type bar segment in rear thereof, a horizontal shaft in rear of said segment having upwardly extending arms, 80 yielding feeding pawls hinged to said arms, a laterally shifting bar in rear of the type bar segment and having cam surfaces adapted by the shifting of the bar to be engaged directly with the feeding pawls to disengage 85 said pawls from said ratchets and spring retaining pawls adapted to be retracted by said feeding pawls.

2. Ribbon feeding mechanism comprising 90 a horizontal ratchet having teeth on its upper face, a horizontally reciprocable feeding pawl coacting with the teeth of said ratchet, and a spring pressed retaining pawl pressing down on said feeding pawl and having a toothed end extending beyond said feeding pawl and into engagement with said ratchet. 95

3. Ribbon feeding mechanism comprising 100 a horizontal ratchet having teeth on its upper face, a horizontally reciprocable feeding pawl coacting with the teeth of said ratchet, a spring pressed retaining pawl pressing down on said feeding pawl and having a toothed end extending beyond said feeding pawl and into engagement with said ratchet and a shifting bar for lifting said feeding pawl and thus causing said feeding pawl to 105 retract said retaining pawl.

4. Ribbon feeding mechanism comprising 110 horizontal ratchets having teeth on their upper faces, horizontally reciprocable feeding pawls adapted to rest upon the ratchets, means for reciprocating the feeding pawls, spring pressed retaining pawls bearing down upon the feeding pawls and having toothed ends adapted to extend into engagement with the ratchets, and a laterally 115 shiftable bar having cam surfaces arranged upon the shifting of the bar, to be engaged with the feeding pawls to lift said feeding pawls and the retaining pawls which rest upon the feeding pawls from engagement 120 with the ratchets.

JESSE ALEXANDER.
